UNITED STATES PATENT OFFICE.

CHARLES M. NESS AND CHARLES T. THOMPSON, OF PHILADELPHIA, PENNSYLVANIA.

RACKET-PRESS.

1,226,986.

Specification of Letters Patent. Patented May 22, 1917.

Application filed April 27, 1916. Serial No. 93,822.

To all whom it may concern:

Be it known that we, CHARLES M. NESS and CHARLES T. THOMPSON, of Philadelphia, in the county of Philadelphia and State of Pennsylvania, have invented certain new and useful Improvements in Racket-Presses, whereof the following is a specification, reference being had to the accompanying drawings.

10 Our invention relates to mechanism for placing the sides of a racket, such as is used in playing lawn tennis, or similar implement, under pressure when the implement is not in use, in order that warping may be prevented. It is important that such a racket press be relatively light and of relatively small bulk. Our press accomplishes its ends having regard to these limitations. It is characterized by the central pin uniting two 15 opposed clamping members, said pin being small enough to pass freely between the meshes which form the stringing of racket. The pin is readily detachable from one of the clamping members in order to permit 20 the racket to be placed within or removed from the press, and is so united to the other clamping member that the needed pressure to prevent warping may be quickly created.

In the accompanying drawings, Figure I, 25 represents a tennis racket with our device applied thereto.

Fig. II, is a longitudinal central section through the same, and

Fig. III, is a sectional view along the line 30 III—III of Fig. I.

The clamping members 1, and 2, form respectively the upper and lower elements of the press. They may be of any convenient form and construction large enough to exert 40 pressure at the proper points on the rim of the racket, and of sufficient stiffness to transmit this pressure evenly from the center of the press to the rim. Within these limitations each clamping member may be formed 45 of any convenient shape, preferably of metal in order to possess the required lightness and rigidity. We have found a convenient construction to be that of a spider frame with radiating arms 3, 3, reaching from the center to the rim of the racket. To stiffen 50 these arms they are preferably made in the form of webs lying in a plane at right angles to that of the racket, and they are fitted with enlargements 4, at the outer ends lying

in the plane of the rim of the racket, thus 55 affording convenient pressure surfaces adjacent to the rim. As shown these arms are arranged in pairs united centrally, the central uniting portions 5, being turned up from, and forming the sides of, a central 60 plate 6.

Thus far the construction of both clamping members is substantially identical.

The upper clamping member has its plate 6, centrally pierced to freely receive the pin 65 7. This pin has a smooth surface where it passes through the meshes of the racket, in order to prevent wear upon the stringing, and is sufficiently small to readily pass through said meshes. This pin carries upon 70 its upper end a sleeve 8, in threaded engagement with the upper end of the pin, whereby the proper vertical adjustment between the two may be accomplished, the head of the pin being provided with a transverse screw 75 driving slot to facilitate this adjustment.

The sleeve 8, is flanged at either end and receives between the flanges the opposed circular bosses 9, mounted upon the inner sides of the bifurcated ends 10, of the hand lever 11, which is mounted upon pivots 12, passing through the turned up sides 5, of the central plate 6. The pivots 12, are eccentric in relation to the bosses 9, as best seen in Fig. III, whereby rotation of the 85 lever arm 11, on its pivot, effects a cam motion exerting pressure upon the sleeve 8, to draw pin 7, up or down in relation to the plane of the clamping member 1.

The other end of the pin 7, passes through 90 a central aperture in the central plate 6, of the clamping member 2, and is there releasably secured by a pin 15, which fits in a slot 16, at the end of the pin 7, and which also slides within a suitable aperture in the 95 central turned up side 5, of the plate 6, its escape and loss being prevented by a stop 17.

When a racket is to be placed under pressure one of the clamping members is placed upon either side, the pin 7, being properly 100 inserted centrally through one of the meshes of the stringing. The lower end of the pin is then secured to the lower clamping member by engaging the pin 15, with its slotted lower end. Thereupon the lever 105 arm 11, which has previously been occupying a position in which the sleeve 8, is in contact with the central plate 6, of the up-

per clamping member, is turned upon its pivot, so as to exert a powerful cam action, drawing the sleeve away from the plate 6, to the position shown in Fig. II, where the 5 mechanism comes to rest with the clamping parts powerfully compressed upon the rim of the racket between them.

The amount of the pressure thus determined is dependent upon the position of 10 the sleeve on the pin, and in order to accommodate this to any individual racket, the proper adjustment is made by turning the threaded end of the pin within the sleeve. When this adjustment has once 15 been properly made for any particular racket, it should remain constant, the clamping members being thereafter applied to that racket as previously described, an application which is very easily and quickly 20 made.

We have already referred to some of the advantages of a racket press such as we have described. The central connection between the two clamping surfaces lessens the 25 size and weight of the parts. The smooth pin for establishing this central connection by passing through the meshes of the stringing of the racket, is free from any tendency to injure the gut. The cam action 30 which is interposed between the upper clamping member and the pin, produces powerful and positive pressure quickly applied to a predetermined limit, and this is what is necessary to effectively prevent any 35 warping of the racket.

The press is not bulky, being small enough to be inserted with the racket in an ordinary racket cover. It is not heavy, and its method of application is so simple 40 as to be capable of being properly used by any one without fear of injuring the racket.

Copies of this patent may be obtained for five cents each, by addressing the "Commissioner of Patents.
Washington, D. C."

Having thus described our invention, we claim:

1. In a racket press, the combination of opposed clamping members; a pin connecting said clamping members centrally; means for attaching and detaching one end of said pin to or from one of said clamping members; and means interposed between the other end of said pin and the other of said clamping members, whereby the distance between the clamping members may be adjusted and means whereby tension is exerted through said pin to draw the clamping members together. 50

2. In a racket press, the combination of clamping members; a pin centrally uniting said clamping members, capable of passing through the mesh of the racket strings; means for adjusting said clamping members in relation to said pin, and a cam lever whereby pressure may be exerted through said pin to draw said clamping members together. 55

3. In a racket press, clamping members 65 united centrally by a pin capable of passing through the mesh of the racket strings; a sleeve adjustably set on one end of the pin; a lever pivoted to one clamping member and having a cam surface engaging said 70 sleeve, whereby pressure may be exerted by throwing said lever to draw said clamping members together to an extent determined by the adjustment of the sleeve on the pin.

In testimony whereof, we have hereunto 75 signed our names at Philadelphia, Pennsylvania, this twenty-fifth day of April, 1916.

CHARLES M. NESS.

CHARLES T. THOMPSON.
